SIGNAL TRANSMISSION SYSTEM

Sydney N. Baruch, New York, N. Y., assignor to
H. Curab Inc., a corporation of New York

Application August 13, 1931, Serial No. 556,921

8 Claims. (Cl. 250—17)

This invention relates to an improved transmission system for signalling whereby a most economical utilization of the available frequency spectrum is effected.

5 An object of my invention is to provide an improved transmission system designed to transmit a radio wave of constant frequency composed of two component portions which are relatively displaced with respect to each other in regard to 10 phase of a varying degree, said displacement being controlled in accordance with the signals imposed upon the system. In its broad aspects my invention contemplates the radiation of a wave of constant frequency from one antenna. A second wave of the same frequency is maintained in 15 synchronism with the first wave. This second wave is modified in phase by means of a circuit controlling element, which may be of the nature of a critically variable condenser as disclosed in 20 my copending application, Serial No. 333,901, filed January 21, 1929. This element serves the purpose of displacing the second wave in phase with respect to the first, within the limit of a single cycle, in accordance with the signals impressed upon the variable capacity. These 25 signals may assume the form of sound waves or may be adapted for purposes of telegraphy. This modified wave is radiated from a second antenna. This practice results in the radiation of two component waves of constant frequency with the 30 phase position of one variably shifted with respect to the other. When these waves combine in a receiving antenna, the original signals are reproduced by the proper rectification of the 35 combined radio frequency wave.

Other objects and purposes will appear from the more detailed description in the following specification, in conjunction with the accompanying drawings.

40 In the drawings:

Fig. 1 illustrates an embodiment of the transmitting station embraced by my invention.

Fig. 2 schematically illustrates a receiving station in cooperation with my transmitting station.

45 Fig. 3 illustrates another form of my invention.

Fig. 4 illustrates the form of my invention used in conjunction with a push-pull output circuit.

Fig. 5 illustrates my invention wherein the energy output is effected through amplifiers upon 50 which is disposed a unique differential capacity control.

Fig. 6 is a modification of the circuit portion K—L—M—N embodied in Fig. 5 and which may be substituted therefor.

55 In Fig. 1 is illustrated an oscillating circuit 10,

comprising an electronic tube such as a thermionic triode embodying the grid 11, hot electrode or filament 12, and cold electrode or plate 13, with suitable A-battery 14 and B-battery 15 connected thereto in the usual manner. The plate 60 circuit includes an inductance 16, which may be variable, as is well known in the art. Condenser 17 is connected across coil 16. A piezo-electric crystal 19 is connected in the input circuit of the oscillating audion. Resistance 18 and an inductance 18' are connected in shunt to the crystal between the grid and filament of the audion. The frequency of the oscillating circuit is controlled by the crystal 19 in the input circuit although the position of that element may be varied as desired. The energy of constant frequency from this circuit is radiated from antenna 16'.

The other circuit 20 comprises similarly a thermionic triode embodying the grid 21, hot electrode 22, and cold electrode 23, with suitable 75 A- and B-batteries 24 and 25, respectively, and an inductance 26 in the plate circuit which may also be adjustable in a manner well known in the art. A condenser 27 is connected across the plate circuit. The input circuit of the triode comprises 80 a resistance 28 in series with a coupling inductance 29, with a condenser 30 in shunt to this circuit. Coupling inductance 29 is furthermore associated with an inductance 31 in the plate circuit of the oscillating circuit 10 which acts as 85 a priming or entraining means for the oscillations generated in circuit 20 to force the same into synchronism with the oscillations in circuit 10. However the input circuit is varied by means of a variable capacity microphone which is connected by means of conductors 43 and 47 across condenser 30. This variable capacity is slight enough to vary the constants of the input circuit without changing its frequency, which effects a 90 phase displacement of the oscillations in this circuit with respect to those normally generated therein. The specific construction of the microphone is disclosed in detail in my application, Serial No. 333,901, filed January 21, 1929. The 95 variable control upon the oscillating circuit 20 is evidenced in the output coil 26, and is radiated from the antenna circuit 26'.

It is not essential for the operation of my system that the controlled oscillating circuit should generate its own oscillations primed by the controlling circuit. The controlled circuit which is modified in phase may be an amplifier of the original energy. Thus in Fig. 3, is illustrated an oscillating circuit 10, generated by a piezo-electric crystal controlled audion in the manner de- 105

scribed in explanation of Fig. 1. In addition to the elements illustrated in Fig. 1, a condenser 39 is associated with the crystal 19. A bias is also imposed upon grid 11 by a battery 49 through a suitable choke 50. The output of oscillating circuit 10, tuned by means of variable inductance 51 and capacity 52 is fed through a series of amplifiers C and D to the radiating circuit R. These amplifying circuits may assume various forms in accordance with the practices well known in the art. As illustrated, these amplifiers are of the three element type with electrodes 57, 58, 59 and 77, 78, 79 corresponding to grid, filament, and plate elements. A bias upon the grid element of amplifier C is provided by battery 55 through inductance 54. Coupling condenser 53 segregates this potential from the circuit 10, at the same time coupling the energy from this circuit to the input of amplifier C. The output circuit of amplifier C, represented by inductance 72 and tuning condenser 71 is coupled to the input of amplifier D by means of coupling condenser 76. The output circuit of amplifier D consisting of variable capacity 80 and inductance 81 is coupled to the reactive elements 83 and 84 of the radiating circuit 83. The amplifying properties of the tubes C and D are controlled by feed-back condensers 70 and 85 associated with portions of inductances 71 and 81, respectively. An amplifier E operates relatedly to amplifier D, having the output of amplifier C impressed across the input circuit of the both of them. A biasing potential for both amplifiers D and E is obtained from battery 75 acting through choke coil 74. The elements of the amplifier E, correspond to those of amplifier D and the output therefrom is radiated from another radiating antenna R'. However the microphone condenser 40 is connected across the tuning condenser 80', which serves to vary the phase position of the radio-frequency wave in the output of circuit of amplifier E with respect to that of amplifier D. The resulting radio frequency waves radiated independently are thus radiated with a varying phase displacement controlled in accordance with the signals imposed upon the microphone condenser 40.

My system is also adapted for application in the case that normally two-waves are radiated which are displaced by 180 degrees. Fig. 4 illustrates a type of push-pull amplifier to effect such a transmission. The portion of circuit 3 to the left of line A—A in Fig. 3, may be used with the amplifying system as illustrated in Fig. 4. The output of amplifier C is capacitively coupled with the push-pull amplifier F—G through condensers 87 and 87'. A grid biasing potential for the grids 90 and 90' is obtained by battery 88 acting through chokes 89 and 89'. The filaments 98 and 98' are energized by battery 97. Source of potential 96 constitutes the common plate supply for the plates 91 and 91'. Of course the specific mode of energization for the various circuits may be modified as desired, the herein-described showing being the simplest. The output circuits of amplifiers F and G, 100 and 100', may be tuned by variable condensers 94 and 94' in conjunction with inductance elements 93 and 93', respectively. Feedback condensers 92 and 92' cooperating with inductance portions 95 and 95' control the amplification properties of the two circuits. The output energies of the two circuits F and G are in turn transferred to antennæ R and R' from which they are radiated. Condenser microphone 40 is connected across con-

denser 94' in circuit G. Thereby the normal relationship existing between circuits F and G is disturbed. The phase of the radio-frequency wave radiated from R' varies from its normally opposed position to that radiated from R within the limit of a single cycle in accordance with the signals impressed upon the microphone condenser 40.

A unique form of control of my modulated energy is illustrated in Fig. 5. The portion of the circuit on the left of line A—A in Fig. 3 may be used with the amplification stages illustrated in this figure. Amplifier H, of the same general type as explained in detail in conjunction with Figs. 3 and 4, is coupled to the output of circuit C through coupling condenser 104. The amplifier circuit I is connected at its grid to the output of circuit C through condenser plate 108 of microphone condenser 40 intermediate plates 107 and 109 connected across the output circuit of amplifier C. In the normal state of this circuit, only circuit H is receiving energy from circuit C and transferring the same to the radiating antenna R. Circuit I, connected with intermediate plate 108, receives no energy since the potentials impressed upon the latter are equal and of opposite phase. However a movement of plate 108 in either direction will cause a preponderant effect thereupon of either of the two external plates. This effect may be so critically designed that a transfer of energy of varying phase displacement may be accomplished to amplifier I and from there to the radiating antenna R'.

A modification of the condenser microphone control described in conjunction with Fig. 5 is illustrated in Fig. 6. This circuit may be substituted for the portion enclosed in the block K—L—M—N with the corresponding conductors X, Y, and Z in Fig. 5, connected to X', Y' and Z' in Fig. 6. A talking circuit 114 is illustrated comprising a microphone 115 and source of potential 116. Electromagnets 117 of equal strength but of opposite polarity control the movable condenser plates 112 and 113 cooperating respectively with fixed plates 111 and 110 in a polarized manner. Thus at the instant when plate 112 would be drawn away from plate 111, plate 113 would be attracted toward plate 110. In the normal position of the condensers, conductor Z' would have no potentials impressed upon it, as explained in conjunction with Fig. 5. However voice currents upon microphone 115 act to disturb the normal condition of the conductor feeding the input circuit of amplifier I to cause a radio wave to be radiated from its associated antenna R', which is displaced in phase from that radiated from antenna R, in Fig. 5.

As a result of the operations hereinbefore described, two sources of energy of the same frequency but relatively displaced in phase, are transmitted from the independent antennæ. A receiving antenna 60 is designed to pick up these energies, and by means of coupling elements 61 and 62, the variable amount of energy imposed upon the receiving antenna is suitably detected in receiver 63, and the original sounds are reproduced in receivers 64 or an equivalent loud-speaker. The audio-frequency wave reproduced by the receiver 63 will depend upon the combination of the energies, and particularly with respect to the relative phase positions of these energies. The mode of operation may be so adjusted that a faithful reproduction of the sounds imposed at the transmitting end may be had at the receiving end.

My system is as well adapted for telegraphy as telephony. Condenser 40 may be replaced by an ordinary key-switching condenser which is so designed as to shift the phase of the wave generated in circuit 20 from that generated in circuit 10 within the limits of a single cycle. A suitable chopper is employed at the receiving station. The signals of the detected energies of different amplitudes, depending upon whether the switching key is effecting a phase displacement of one of the radiated sources of energy, correspond to the manipulation of the key at the transmitting station.

While I have described my invention in certain preferred embodiments, I desire it to be understood that modifications may be made and that no limitations upon the invention are intended other than are imposed by the scope of the appended claims.

20. What I claim is:

1. The method of signal transmission comprising the generating of a high frequency wave, controlling a second high frequency wave of the same frequency as the first wave by said first wave, radiating said first high frequency wave, modifying the phase position of said second wave relatively to said first wave within a single cycle in accordance with signals, and radiating said modified high frequency wave.

2. The method of signal transmission comprising the generating of a high frequency wave, controlling a second high frequency wave of the same frequency as the first wave by said first wave, radiating said first high frequency wave, modifying the phase position of said second wave relatively to said first wave within a single cycle in accordance with signals, radiating said modified high frequency wave, and receiving said high frequency waves in a receiver tuned to their common frequency.

3. The method of signal transmission comprising the generating of a high frequency wave, controlling the generation of a second high frequency wave of the same frequency as the first wave by said first wave, radiating said first high frequency wave, modifying the phase position of said second wave relatively to said first wave within a single cycle in accordance with signals and radiating said modified high frequency wave.

4. The method of signal transmission comprising the generating of a high frequency wave, amplifying said wave at two independent points, radiating said wave at one of said points, modifying the phase position of the wave at the second of said points relative to the wave radiated from said first point within a single cycle in accordance with signals, and radiating said modified high frequency.

5. In a signal transmission system, an oscillating circuit of constant frequency, an output circuit therein, radiating means for the energy developed in said output circuit, a second oscillating circuit associated with said output circuit whereby said second oscillating circuit is maintained in synchronism at said frequency with said first oscillating circuit, an output circuit in

said second oscillating circuit, independent radiating means for the energy developed in said second circuit, and circuit controlling means in said second circuit for modifying the phase position of the output of said second oscillating circuit with respect to the output of said first oscillating circuit.

6. In a signal transmission system, an oscillating circuit of constant frequency, an output circuit therein, radiating means for the energy developed in said output circuit, a second oscillating circuit associated with said output circuit whereby said second oscillating circuit is maintained in synchronism at said frequency with said first oscillating circuit, an output circuit in said second oscillating circuit, independent radiating means for the energy developed in said second circuit, circuit controlling means in said second circuit for modifying the phase position of the output of said second oscillating circuit with respect to the output of said first oscillating circuit, and means for receiving the energies of said two output circuits tuned to their common frequency.

7. In a signal transmission system, an oscillating circuit of constant frequency, comprising a thermionic tube circuit, a piezo-electric crystal in said input circuit, an output circuit, radiating means for the energy developed in said output circuit, a second oscillating circuit comprising a thermionic tube and an input circuit, means for coupling said output circuit with said last mentioned input circuit whereby said second oscillating circuit is maintained at said frequency of said first oscillating circuit, an output circuit in said second oscillating circuit, independent radiating means for the energy developed in said last mentioned output circuit, and circuit-controlling means in said second oscillating circuit for modifying the phase position of the output of said second oscillating circuit with respect to the output of said first oscillating circuit.

8. In a signal transmission system, an oscillating circuit of constant frequency, an output circuit therein, an amplifier connected to said output circuit, radiating means for the energy developed in said amplifier, a second amplifier connected to said output circuit, said latter connections comprising differentially controlled capacitance normally set to effect no energy transfer between said output circuit and said second amplifier and adapted to transfer a wave displaced in phase within the limits of a single cycle from that transferred to said first amplifier in response to signals, said capacitance comprising a microphone circuit, two polarized electromagnets in said circuit, two condensers each having a fixed and movable plate associated with said electromagnets, the fixed plates of said condensers being connected across the output circuit, and the movable plates, adapted to be differentially controlled by the electromagnets, connected to the input circuit of the second amplifier, and means for independently radiating the energy of said second amplifying circuit.

SYDNEY N. BARUCH.
